UNITED STATES PATENT OFFICE

HENRY E. KIP, OF LAKEWOOD, OHIO, ASSIGNOR TO NATIONAL CARBON COMPANY,
INC., A CORPORATION OF NEW YORK

DESIGN FOR AN ELECTRIC-ARC LAMP

Application filed April 28, 1930. Serial No. 35,412. Term of patent 7 years.

To all whom it may concern:

Be it known that I, HENRY E. KIP, a citizen of the United States, residing at Lakewood, in the county of Cuyahoga, State of Ohio, have invented a new, original, and ornamental Design for an Electric-Arc Lamp, of which the following is a specification, reference being had to the accompanying drawing, forming part thereof, and wherein

the single figure is a perspective view of a canopy showing my new design.

The canopy is octagonal in shape and is symmetrical about its vertical axis.

I claim:

The ornamental design for an electric-arc lamp substantially as shown and described.

HENRY E. KIP.
